UNITED STATES PATENT OFFICE.

CONRAD SCHNEIDER, OF NEW YORK, N. Y., ASSIGNOR TO INTERNATIONAL BOX WRAPPER CORPORATION, OF NEW YORK, N. Y., A CORPORATION OF NEW YORK.

BOX-WRAPPER FOR PACKAGES.

1,292,891.

Specification of Letters Patent. Patented Jan. 28, 1919.

Application filed April 9, 1918. Serial No. 227,496.

To all whom it may concern:

Be it known that I, CONRAD SCHNEIDER, a citizen of the United States, and a resident of the city of New York, borough of 5 Manhattan, in the county and State of New York, have invented a new and Improved Box-Wrapper for Packages, of which the following is a full, clear, and exact description.

10 This invention relates to wrappers or containers for packages or parcels and has particular reference to means for wrapping packages in laundries, tailor shops, haberdasheries, drygoods stores, or the like where 15 rapidity of operation is important as well as safety or protection is provided for the goods.

Among the objects, therefore, of the invention is to provide a wrapper for packages that shall combine all of the features of protection afforded by a well made straw board box when properly assembled and wrapped with a paper wrapper.

More specifically stated I provide a combined straw board box and sheet of wrapping paper of such a nature that the supply of the wrappers will be retained in flat form, thus occupying a minimum amount of space, until the package is to be wrapped, 20 than one of my improved wrappers with the commodity placed thereon and to be wrapped therein will be laid upon the wrapping table or counter and the combined wrapper may be readily and directly rolled 25 or folded into box form making a stiff neat wrapped package and one in which the straw board portion of the wrapper will serve automatically first to carry the wrapping sheet end portions into a neat folding or 30 overlapping position and secondly will so reinforce or stiffen the entire structure as to reduce the liability of the package to bend, twist or crush to a minimum.

A still further object of the invention is 35 to provide a combined straw board box structure and paper wrapper in such a manner as to provide that the box structure shall facilitate the manipulation of the paper sheet cover and that said cover shall constitute a means to hold the box in comparatively rigid strain resisting position.

With the foregoing and other objects in view the invention consists in the arrange-

ment and combination of parts hereinafter described and claimed, and while the invention is not restricted to the exact details of construction disclosed or suggested herein, still for the purpose of illustrating a practical embodiment thereof reference is had to the accompanying drawings, in which like reference characters designate the same parts in the several views, and in which—

Figure 1 is a plan view of one of my improved box wrappers complete, inner face upward.

Fig. 2 is a perspective view indicating the direction in which the box wrapper is folded first from the flat form; and

Figs. 3 to 7 inclusive represent succeeding stages of the same operation in regular order with the wrapping or folding completed in the last figure ready for a wrapping twine, gum binding strip, or other like sealing means.

Referring now more specifically to the drawings, I show my improvement as comprising two main portions namely an inner box-like structure 10 of straw board or equivalent relatively cheap stiff material and an outer covering sheet 11 of any suitable material such as Manila paper or the like which may, if desired, carry printed matter on its outer surface. These two parts preparatory to the wrapping operation, preferably at the factory, are secured permanently together in 25 the relative positions indicated in Fig. 1, by any suitable means so that they shall always be handled thereafter as single wrapping units, and preferably in flat form for convenience of storage, transportation, handling or the like.

The box portion 10 is preferably of the form or character indicated and comprises a rectangular bottom panel 12; two side panels 13 and 14 bendable around the edges of 30 the bottom panel along the bending lines 15 and 16 respectively; top panels 17 and 18 hinged to the outer or upper edges of the side panels 13 and 14 along the bending lines 19 and 20 respectively, and finally a 35 pair of end panels 21 and 22 hinged to the ends of the top panel 18 along the bending lines 23 and 24 respectively. The whole length of the box structure in the blank therefore is from the edge 25 to the edge 26. 40

The cover strip 11 of paper or the like

in the form illustrated is of rectangular form and has a width in one direction exactly equal to the combined length of the top panel 18 and the attached end panels 21 and 22. In the other direction, however, the cover sheet is enough longer than the length between the edges 25 and 26 to provide the overlaps 27 and 28. Thus I have shown the overlap 27 folded directly over the line 25 10 and upon the inner face of the top panel 17, while the overlap 28 is folded around the line 26 and upon a narrow portion of the inner or top face of the top panel 18 and end panels 21 and 22. The means I have indicated to secure the box and cover sheet portions together permanently consists of pairs of staples 29 and 30. The staples 29 are passed downward through the overlap 27, panel 17 and clenched on the outer surface of the cover sheet as shown in Fig. 2, thus leaving a smooth finish on the inside of the box. The staples 30 are passed through the outer face of the cover sheet then through the top panel 18 and finally 25 through the overlap 28, the points of the staples being clenched upon what becomes the inner face of said overlap leaving a smooth finished surface of the staples 30 on the outside of the finished wrapper as 30 plainly indicated in the figures of Sheet 2.

I preferably round the points or free corners of the end panels 21 and 22 as indicated at 31 so as to practically obviate the likelihood of these points puncturing through the 35 corner portions of the cover sheet in the finished package.

The use of the improvement and manner of operation may be briefly set forth as follows: The goods or commodity to be 40 wrapped being placed upon the inner or top surface of the bottom panel 12, the operator grasping the side and top portions of the wrapper will bring these portions up over the commodity as suggested in Fig. 2. The 45 top panel 17 of the box and the cover sheet secured thereto come into place first over the commodity, while the opposite or top panel 18 will follow immediately bringing the overlap 28 directly down upon the top 50 panel 17 and the edge 26 coinciding with the bending line 19 as indicated in Fig. 3. So far the wrapper is formed into tubular form of rectangular cross section, both ends being wide open. The end panels 21 and 22 55 of the box structure being attached to the top panel 18 and lying in the same plane are then at the top. The operator then holding the body portion of the package steady will bend the end panels 21 and 22 in succession directly downward into the position of Fig. 4 where the free edges of these panels will abut squarely against the end edges of the panels 12, 13 and 14, and within the surrounding cover sheet. This step completes the box structure,—top, bottom, sides

and ends. The bending or breaking downward of the end panels around bending lines 23 and 24 as just set forth causes the end portions of the cover sheet to come automatically into the partial folded position shown 70 in Fig. 4, so that the final wrapping operation may be easily and quickly completed, the triangular wing portions 32 being folded inward against the end panels by the operator's fingers as usual in the wrapping 75 of packages, but much more easily than in the ordinary package because of the action of the end panels aforesaid, leaving the final end flap or tongue 33 to be brought upward as shown in Figs. 6 and 7 ready for the cord 80 or other sealing means.

It will thus be seen that I provide a box wrapper or a combined box and cover sheet of such a nature and adapted for such operation as to embody all of the advantages 85 of a complete box of the form in which the bottom, side and end panels are fixed in permanent form and having a loose cover, or in the form having interlocking tongues or the like, such as are commonly used by 90 tailors and others for packing suits, and a separate wrapping sheet. Moreover this improvement is not only quicker to operate but it produces a stiffer finished structure than would be realized if a knock down suit box 95 were employed and subsequently wrapped with a sheet of paper, for the reason that the two structures 10 and 11 mutually coöperate in such a manner as to provide a stiffer box 100 structure than the usual knock down box and because the box structure itself acts to determine the folding lines for the cover sheet, and finally the cover sheet serves to hold the box structure in form.

I claim:

1. The herein described combined box and cover sheet comprising a main rigid body portion having top, bottom, side and end panels all united along bending lines, a cover sheet of rectangular form having end 110 portions arranged to fold over the edges of the top panel of the body portion, said cover portion being secured to one of said panels by staples passing from the inner side of the panel and being clenched on the outside and the other top panel having staples passed through the cover portion and the panel and being clenched on the inside whereby the ends of the staples are hidden when the box is folded.

2. The herein described combined box and cover sheet comprising a main body portion of rigid material having top, bottom, side and end panels united along scored bending lines, the two end panels being formed at 125 continuations of a top panel, a cover sheet of rectangular form as wide as the combined length of the top panel and the attached end panels aforesaid, the length of the cover being sufficient to cover all of the outer sur- 130

face of the box portion and to provide end portions adapted to be folded over the edges of the top panels of the main body portion and means for securing said folded over 5 portions to said panels.

3. The herein described box wrapper comprising a box structure of rigid material having top, bottom, side and end panels united along scored bending lines, the top, 10 bottom and side panels being foldable into tubular form around parallel lines, a cover sheet of suitable proportions to cover the exterior surface of the box structure, and means to fasten the end portions of the 15 cover sheet to portions of the box structure whereby the cover sheet will be rolled into tubular form coincidentally with the rolling of the box structure and whereby the folding of the end panels subsequently into 20 box formation will carry therewith portions of the end flaps of the cover sheet, the end panels of the box structure being brought

squarely against the end edges of the bottom and side panels.

4. The herein described combined box and 25 cover sheet comprising a main body portion of rigid material having top, bottom, side and end panels united along scored bending lines, the two end panels being formed as continuations of a top panel, a 30 cover sheet of rectangular form as wide as the combined length of the top panel and the attached end panels aforesaid, the length of the cover being sufficient to cover all of the outer surface of the box portion 35 and to provide end portions adapted to be folded over the edges of the top panels of the main body portion, means for securing said folded over portions to said panels, the inner corner of the end panels being rounded to prevent their puncturing the cover 40 during the folding of the box.

CONRAD SCHNEIDER.
